UNITED STATES PATENT OFFICE.

ANDRÉ FELIX JACQUEMIN, OF SAUCOURT PAR DOULAINCOURT, FRANCE.

FURNACE ADAPTED FOR THE HEATING AND UNWINDING OF ROLLS OF WIRE.

Application filed June 28, 1926, Serial No. 119,204, and in France July 8, 1925.

My invention relates to improvements in furnaces adapted for the heating and the unwinding of rolls of wire according to my said improvements, the part of the furnace chamber which is situated above the reel carrying the roll of wire to be unwound, is upwardly extended and will thus contain a certain number of rolls of wire which become gradually heated while the roll of wire placed on the reel is being unwound. These preliminarily treated rolls are maintained in the horizontally superposed position by means of removable spindles which are optionally cooled by a current of water and which extend from the walls of the chamber at the proper places. An aperture, closed by a cover, is provided at the upper part of the chamber for the insertion of the rolls of wire.

By withdrawing the spindles which support one of the rolls of wire, this roll can be dropped into position on the next lower level, and so on until it attains the reel, and the wire thereon which is heated to the proper degree is finally unwound through a lateral aperture analogous to the one above described.

The improvements forming the subject matter of the present invention are disclosed by way of example according to the construction represented in the appended drawings.

Fig. 1 is a sectional elevation of the improved furnace.

Fig. 2 is a cross section on the line II—II of Fig. 1.

Fig. 3 is a lengthwise section on a larger scale of one of the spindles serving to support the rolls of wire in the furnace.

In Figs. 1 and 2, 7 is the metallic reel situated at the centre of the furnace which is heated by suitable means. The reel comprises an external flange or base 12 adapted to receive the roll of wire to be heated, and the wire can be unwound through the lateral conduit 19.

The chamber 3 of the furnace is upwardly extended as shown in Fig. 1 so as to contain the rolls of wire 13 which are superposed and are maintained by a plurality of removable spindles 40 which traverse the wall of the furnace through tubes 41 which are imbedded in the wall.

The top of the furnace chamber is closed by a cover 42 in such manner as to provide an aperture 43 at the side which can

be closed by a movable plate 44. The size and shape of the aperture, are such as to allow the insertion of a roll of wire, and its insertion into the proper position may be facilitated by the use of the curved guide plate 47.

The furnace being heated by the usual means, and the reel 7 as well as the spindles 40 being provided with their rolls of wire, it will be observed that while the roll of wire on the said reel is being unwound through the aperture 19, the other rolls 13' placed above it will be more or less subjected to the action of heat and hence will be gradually heated. When the roll 13 is entirely unwound, I withdraw the spindles 40 holding the roll 13' situated immediately above, so that the roll will drop upon the reel, and since this roll of wire has now become considerably heated, the unwinding operation may be commenced almost at once.

In the meantime I again insert the spindles 40 which served to hold this roll of wire, and by a like action I bring upon them the roll which is situated above. The same operation is performed for the upper roll, and a fresh roll of wire is then inserted through the aperture 43.

In this manner I take advantage of the time required for the unwinding of a roll of wire for the heating of the rolls which are to be subsequently unwound. It will be thus observed that the furnace which thus operates in a continuous manner will have an output and an efficiency which are much superior to what can be obtained with the known furnaces.

To obviate the rapid deterioration of the spindles 40 which are directly exposed to the flames, the said spindles may be constructed as shown in Fig. 3 and may comprise in the interior a tube 45 providing for a water circulation, the water being supplied through the hose 46.

I claim:

1. A furnace of the character described comprising a reel construction at the bottom of the furnace for supporting a coil of wire and a plurality of supports arranged above the reel for successively supporting coils of wire in their movement toward said reel structure.

2. A furnace of the character described comprising a furnace casing, heating means at the bottom of the casing, a reel structure arranged in the casing above the heating

means and a plurality of removable supports for supporting coils of wire previously to being deposited on said reel structure.

3. A furnace of the character described comprising a furnace casing, heating means at the bottom of the casing, a reel structure arranged in the casing above the heating means and a plurality of removable supports for supporting coils of wire previously to being deposited on said reel structure, and means for cooling said support in a furnace structure.

4. In combination, a furnace casing, a reel arranged at the bottom of the casing, means for passing heat around the reel and a plurality of superimposed supports above the reel arranged to successively support a roll of wire in its movement toward said reel.

5. In a structure of the character described, a reel means for passing heat around the reel, and a plurality of supports adjustable for passing coils of wire in a step by step movement toward said reel and finally depositing the coil upon the reel.

6. In a structure of the character described, a reel means for passing heat around the reel, and a plurality of supports adjustable for passing coils of wire in a step by step movement toward the reel and finally depositing the coil upon the reel, and water conveying means passing into and out of the supports for cooling the latter.

In witness whereof I have hereunto set my hand.

ANDRÉ FELIX JACQUEMIN.
